CASE LOADER

Alvin F. Hendricks and Robert F. Wiley, Anderson, Ind., assignors to Lynch Corporation, Anderson, Ind., a corporation of Indiana

Application September 22, 1954, Serial No. 457,686

16 Claims. (Cl. 53—166)

This invention relates generally to a case loader, and more particularly to a novel machine for loading groups of bottles into empty cases in a continuous series of consecutive groups.

The present invention provides an improved machine for performing case loading operations similar to those disclosed and described in co-pending Curran and Kerker application, Serial Number 457,386, filed September 21, 1954, having a common assignee with the present case.

It is a primary object of the present invention to provide an improved case loading machine wherein a predetermined loading pattern of bottles may be positioned and held stationary at a loading station by means of a bottle-gripping head, and an empty case may be elevated upwardly around the pattern in close surrounding relation by means of a case elevator, whereby upon release of the bottles from the gripping head there will be little or no remaining height for the bottles to fall onto the case bottom in order to complete the loading of the bottles within the case.

It is another object of this invention to provide a case loader wherein all handling operations performed with the bottle loading pattern, after its formation, are effected entirely by pneumatically controlled means.

It is a further object of this invention to provide a case loader which is entirely automatic in its operation, and which incorporates control safety means responsive to the proper performance of every machine function, whereby completely fail-safe operation is achieved.

It is still another object to provide a case loader having a novel conveyor and bottle guide section for feeding a continuous flow of consecutively abutting bottles in adjacent spaced rows, whereby a predetermined forward pattern or grouping may be separated preparatory to loading the pattern into a case, and having automatic means for relieving the forward pressure of the conveyor-fed bottles from the forward loading pattern during and after its formation.

It is still a further object of this invention to provide a case loader having a bottle lift assembly cooperating with the discharge end of the bottle feed conveyor for elevating a separated loading pattern to a position of cooperative relation with a bottle-gripping head preparatory to moving the bottle pattern to a loading station, wherein the bottle lift assembly provides a novel collapsible supporting platform which cooperates with the bottle-gripping head to effect uniform horizontal alignment of the bottle tops regardless of variation in over-all bottle height.

It is yet another object to provide a fully automatic case loader capable of efficient and reliable operation in a continuous manner despite variations in bottle size uniformity, and capable of being readily adjusted to accommodate the case loading of a wide variety of bottle sizes in a wide variety of bottle-multiple patterns.

Further objects and advantages of this invention will become apparent as the following description proceeds and the features of novelty which characterize this in-

2

vention will be pointed out with particularity in the claims annexed to and forming part of this specification.

A preferred embodiment of the invention is shown in the accompanying drawing, in which:

5 Figure 1 of the drawing is a side elevational view, partly broken away and in section to show interior detail, of a case loader machine constructed in accordance with present invention;

Figures 21 through 25 are diagrammatic views showing the sequence of mechanical operations performed by the case loader of this invention in loading bottles into cases;

55 Figure 26 is a circuit diagram showing the electrical control circuit for the case loader;

Figure 27 is a diagrammatic front end view of the case loader, showing the location of the various panel boxes for mounting the electrical circuit control means on the case loader; and

60 Figure 28 is an operating chart showing the sequence of operations for the various functions performed by the machine disclosed during a case loading cycle.

65 In Figures 1, 2, and 3 of the drawing we have shown a case loader machine constructed in accordance with the present invention. For convenience of discussion, we have generally indicated the major sections of the machine by letters in the following manner. The machine frame is indicated at A. A bottle feed conveyor and bottle guide section is indicated at B. A mechanical drive section for the bottle feed conveyor is indicated at C.

70

cated at C. A bottle lift assembly adapted to receive bottles from the conveyor and guide section B, and elevate a predetermined pattern or grouping of bottles upwardly, is indicated at D. A transfer head and bottle clamp unit, operative to receive bottles elevated by the lift assembly D and carry them forwardly in suspended relation, is indicated at E. A case elevator assembly for raising an empty case or carton about the suspended bottles held by the head E is indicated at F. The case loading station, where the transfer head of unit E and the case elevator assembly F cooperate to effect case loading, is indicated at G. An empty-case feed section, a loaded-case discharge section, and the mechanical drive for the empty-case feed section are indicated at H, I, and J, respectively.

As best seen in Figures 1 and 2 of the drawing, the bottle feed conveyor and bottle guide section of the machine are supported on a conveyor frame 20 having vertical supporting legs 22 at its rear or receiving end, and being secured to a housing structure portion 24 of the machine frame A adjacent its forward or discharge end. Bottom tie rails and transverse tie channels 26 provide rigid structural bracing for the conveyor frame 20.

A first pair of center guide posts 28 and a second pair of center guide posts 30 are rigidly secured to the sides of the conveyor frame 20. Each pair of guide posts 28 and 30 support a pair of relatively long guide shafts 32, which extend horizontally inwardly over the conveyor frame 20 and terminate in mounting flanges 34 which are rigidly secured to the vertical side walls of a pair of outer guide members 36 and 38. The outer guides 36 and 38 cooperate to form a constricted, straight-walled bottle entry section and an outwardly diverging forward travel section, as clearly seen in Figure 2 of the drawing.

Guide support shafts 40 and 42 are carried by the guide posts 28 and 30, respectively, and extend transversely across the width of the conveyor frame 20. The guide support shafts 40 and 42 carry a pair of guide hangers 41 and 43, which serve to fixedly position and support a center guide plate 44 between the guides 36 and 38 along the straight-walled entry section formed thereby.

A third pair of center guide posts 46 are carried by the conveyor frame at a point slightly forward of its mid-length. A pair of front guide posts 48 are carried by the conveyor frame 20 at a point adjacent its forward or discharge end. A pair of relatively short guide shafts 50, similar to the shafts 32, are carried by the center guide posts 46 and serve to position and support a pair of outer guides 52 and 54. Third and fourth guide support shafts 56 and 58 are carried by the center and front guide posts 46 and 48, and extend transversely across the width of the conveyor frame 20. The guide support shafts 56 and 58 each carry a plurality of guide hangers 60 and 62, respectively. The guide hangers 60 and 62 serve to fixedly position and support a plurality of guide plates, including a relatively long center guide plate 64, and a pair of relatively short intermediate guide plates 66 and 68.

An additional pair of guide supports 70, having relatively short guide shafts 72 provided with mounting flanges 74, serve to fixedly position and support the outer guides 36 and 38 adjacent their forward ends.

The outer guides 52 and 54, and the guide plates 64, 66, and 68, are all formed as substantially straight-walled sections. The rear ends of the outer guides 52 and 54 terminate closely adjacent the forward ends of the outer guides 36 and 38, which are also substantially straight-walled at this point. The outer guides 36, 38, and 52, 54, provide a substantially continuous guide channel adapted to confine a flow of bottles therebetween.

As best shown in Figure 2a of the drawing, the guide

plates 64, 66, and 68 are each provided at their rear edges with a pair of roller brackets 76 and 77, which rotatably support a pair of rollers 78 and 79 on vertical axes. The rear edges of the guide plates 64-68 operate in the manner of spreader gates to direct the bottles into adjacent, spaced rows between the guide plates and outer guides. The rollers 78 and 79 serve to insure the movement of bottles into one row or another without risk of jamming obstruction against the edge of a guide plate. Preferably, the vertical position of the roller brackets 76 and 77 is selected so as to permit the rollers 78 and 79 to engage the bottles at points slightly above and slightly below the label L thereof, as shown, to avoid tearing or marring the label as the bottles are directed into rows.

A conveyor traveling level, having a movement in the direction shown by the arrow, is indicated generally at 80. The conveyor 80 comprises a plurality of link plates 82 (see Figure 1) which are suitably supported in conventional manner on forward (upper) and return (lower) conveyor rails. A sprocket wheel 84 is carried by a suitable shaft 88 at the receiving end of the conveyor 80. The sprocket shaft 88 is suitably mounted for rotation within bearings carried by the conveyor frame 20. A conveyor drive shaft 90 is rotatably supported within suitable bearings adjacent the discharge end of the conveyor 80. The drive shaft 90 carries a sprocket wheel 86, which together with the sprocket wheel 84, serves to engage the link plates 82 for effecting drive of the conveyor 80.

A power sprocket gear 92, also carried by the drive shaft 90, meshes with a link chain 94 driven by a gear 96 on the output shaft 98 of a gear reducer 100. A link chain 102 serves to connect an input shaft of the gear reducer 100 with a drive sprocket gear 104 carried on an output shaft 106 of a motor 108. In this way power from the motor 108 is transmitted to effect continuous drive of the conveyor 80. The drive mechanism for the conveyor 80 is mounted upon the machine frame within the housing portion 24, and is suitably enclosed therein. A removable door panel 110 is provided for purposes of access.

The bottle feed conveyor and bottle guide section B of our case loader machine is provided with two separate means for relieving the pressure which is exerted by the tendency for forward movement of bottles on the conveyor against the forward pattern or grouping of bottles which is to be loaded into a case. First, we provide swinging bottle guides for separating a forward loading pattern from the rows of bottles being fed by the conveyor and wholly eliminating all forward feeding pressure exerted against the loading pattern by the conveyor-fed bottles. A bottle-guide swing-operating cylinder 112 is mounted on the conveyor frame 20 by means of a swing cylinder mounting bracket 114 (see Figure 7). A guide bar bracket 116 is positioned below the swing cylinder 112. A piston rod 118 extends from the swing cylinder 112, and is pivotally attached to the upper end of a swing lever 120. The lower end of the swing lever 120 is pivotally secured to the guide bar bracket 116. The guide support shaft 58 is also pivotally secured to the lever 120 at a point intermediate the ends thereof. Suitable slide blocks and slots 122 are provided by the lever 120 for effecting adjustable pivotal attachment to the elements 118, 116, and 58.

As best seen in Figure 6 of the drawing, the guide hangers 62 are secured to the guide support shaft 58 by means of mounting blocks 126, which provide vertical pivot pins 128 for rotatably suspending the guide hangers 62. The guide hangers 60 of the guide support shaft 56 are similarly provided with mounting blocks 130 having pivot pins 132. The pivot pins 128 and 132 have a sufficiently loose fit within the guide hangers 62 and 60 to allow arcuate swinging of the guide plates about pivot

points lying on the longitudinal axis of the guide support shaft 56.

The second means for effecting relief of bottle feeding pressure is provided in the form of a pair of automatic pressure gates. As best seen in Figure 5 of the drawing, a pair of bottle stop levers 142 and 144 are pivotally mounted on pins 146 to mounting brackets 148 and 150, respectively. The mounting brackets 148 and 150 are fixedly secured to the vertical side walls of the constricted or straight-walled entry portions of the outer guides 36 and 38. The bottles carried by the conveyor through the constricted portion of the outer guides 36 and 38 are aligned in two side-by-side rows, separated by the center guide plate 44.

The bottle stop levers 142 and 144 provide stops 152 and 154 extending at right angles from their free ends. The walls of the outer guides 36 and 38 are formed with suitable slots through which the stops 152 and 154 may extend to engage the corresponding rows of bottles and prevent forward movement thereof. Each of the bottle stop levers 142 and 144 is provided with a gate cylinder 156 having a piston 158 which carries an abutment screw 160 adapted to engage the levers 142 and 144 and pivot them inwardly across the path of travel of the bottle rows. A suitable bias spring 162 normally serves to pivot the levers 142 and 144 outwardly so as to withdraw the stops 152 and 154 and permit the free movement of bottles on the conveyor 80.

The gate cylinders 156 are pneumatically responsive, and when actuated serve to move the stops 152 and 154 inwardly to path-obstructing positions against the bias of springs 162. An air supply line 164 conducts a supply of air to each of the cylinders 156 from an air source supply line 166. The flow of air from the air source line 166 to the air supply line 164 is controlled by means of a control valve 168. A gate 170 extends through an opening in one of the guide plates 38 along the diverging wall portion thereof. The gate 170 is normally biased by means of a spring hinge 172 so as to extend inwardly through the guide plate 38 into the path of movement of the bottles carried by the conveyor 80. An adjustable limit stop 174 is provided to prevent outward swing of the gate 170 beyond a predetermined limiting position. A hinge pin 178 serves to connect the gate 170 to a piston rod 176 of a valve member 180, which is slidably movable within the gate control valve 168.

It will be apparent from Figure 5 that the presence of a sufficient number of bottles within the diverging portion of the guide plates 36 and 38 will serve to cause the gate 170 to be engaged by adjacent bottles and pivoted outwardly through the guide plate 38. Such swinging movement of the gate 170 serves to axially slide the piston rod 176 and valve member 180 toward the valve-open position shown. Air may then flow freely from the air source line 166, through the air supply line 164, to the gate cylinders 156, thereby effecting actuating movement of the stops 152 and 154 to the closed positions shown.

As best seen in Figures 2 and 4 of the drawing, a uniform flow of bottles will be conducted by the conveyor 80 in a pair of side-by-side rows through the constricted entry portion of the outer guides 36 and 38. The two-row flow of bottles will then be permitted to displace outwardly through the diverging portion of the guide plates 36 and 38 toward a four-row flow, as directed by the guide plates 64, 66, and 68 in cooperation with the outer guides 52 and 54. Complete filling of the diverging conveyor portion will serve to actuate the automatic pressure gates, as shown in Figure 5 of the drawing.

It is an important feature of the present invention to provide an initially constricted and then divergent bottle flow path toward a maximum conveyor width accommodating the desired number of side-by-side rows of bottles. The particular diverging guide arrangement shown greatly

facilitates an even bottle flow, and substantially minimizes the possibility of excessive bottle feed pressures against the forward end of the case loader under maximum capacity conditions requiring the conveyor to receive bottles at a faster rate than they can be carried forward and loaded into cases.

It will be apparent that the number of guide plates may be varied to provide the desired number of side-by-side rows of bottles for separation into a loading pattern or grouping. In the particular construction illustrated, 10 four rows are shown to permit the separation of a three-deep forward grouping of twelve bottles for loading into a case. The particular arrangement shown is intended for use in connection with the case loading of relatively large quart-size bottles. By increasing the number of guide plates, smaller bottles may be arranged, for example, in rows of six to permit the selection of a six-deep, six-row pattern of thirty-six bottles to be loaded into a case.

When the bottles have been carried to the forward end of the conveyor 80, they will be discharged onto the bottle lift assembly D, whereby a forward loading pattern of bottles may be elevated upwardly into the transfer head and bottle clamp unit E for movement to the case loading station G. A lift platform is provided beyond the forward end of the conveyor 80, and comprises a plurality of floating or collapsible bottom plugs 190 (see Figures 9 and 10). Each of the bottom plugs 190 provides a pair of bottom rails 192 adapted to engage the bottom of a bottle and support it in a vertical position. A stem 194 (see Figure 9) supports the plug 190 and serves to enclose a spring stud 196 which is biased upwardly by means of a spring 198. The stem 194 is suitably supported by means of a mounting bushing 200 on a base plate 202. The bottom plugs 190 serve to resiliently support a plurality of bottles in vertical position, while permitting depression of the bottles for purposes of aligning the tops of bottles of different vertical heights in the same horizontal plane. In this manner, every bottle is uniformly positioned so as to permit the bottle clamp unit to grasp each bottle at the same point with respect to the cap or crown thereof, irrespective of irregularities in the heights of the bottles.

The base plate 202 is supported by means of channels 204 and a guide bracket 206 which provides edge rails 207 cooperating with vertical guides 208 for up and down movement of the base plate 202. The piston rod 210 of a pneumatic bottle-lift cylinder 212 is connected to the guide bracket 206. A suitable air supply 214 serves to actuate the bottle-lift cylinder 212 for effecting vertical reciprocation of the bottle-lift platform formed by the bottle plugs 190.

A dead plate and stop assembly is provided between the forward end of the conveyor 80 and the bottle-lift assembly. Wear plates 220, having spaced gaps to permit liquid drainage for cleaning purposes, form a horizontal support level upon which the bottles are received and supported as they move from the conveyor 80 to the bottle-lift bottom plugs 190. Bottle-stop brackets (see Figures 6 and 10) serve to suspend a bottle-stop support bar 224 to which a plurality of vertical bottle stops 226 are secured. The bottle stops 226 are rigidly secured between the wear plates 220 and support bar 224 in fixed positions of alignment with the guide plates of the bottle-feed conveyor 80 as the bottle rows move forwardly in their normal course of travel on the conveyor.

A plurality of bottle separators 228 (see Figure 9) are supported on the bottom plug base plate 202 of the bottle lift assembly in alignment with the bottle feed conveyor guide plates and the bottle stops 226. It will be apparent from Figure 2 of the drawing that this alignment of the guide plates, bottle stops, and bottle separators serves to direct a flow of bottles in side-by-side rows onto the bottle lift assembly D.

When it is desired to elevate the bottle lift platform

for raising a loading pattern toward the transfer head and bottle clamp unit E, the swinging bottle guides are actuated to relieve the backed-up bottle pressure exerted against the loading pattern and to stop the forward movement of bottles from the conveyor and dead plate assembly toward the bottle lift assembly. As best seen in Figure 4 of the drawing, actuation of the swing-operating cylinder 112 effects a simultaneous sidewise movement of the guide plates 52, 54, 64, 66, and 68 in an arcuate path about pivot points lying along the longitudinal axis of the guide support shaft 56. The foremost bottles of the rows formed between the swinging guide plates will be moved transversely across the width of the conveyor 80 and wear plates 220 to a position of misalignment with respect to the foremost three-deep pattern of bottles resting on the bottle lift assembly. As the forward ends of the swinging guide plates move in an arcuate path, the foremost bottles immediately prior to the loading pattern will rotate in a rolling movement about the bottles immediately forward of them and against the vertical edge of the bottle stops 226. This rolling movement of the bottles effectively minimizes abrasive sliding between bottles, commonly termed "scrubbing," and prevents damage to the bottle labels.

As indicated by the arrows, the bottles shown in Figure 4 will roll or rotate in a counter-clockwise direction and move sideways a distance of about one-half the diameter of a bottle. At the same time, the rolling or rotating bottles will move slightly in a forward direction. Conversely, as the swinging bottle guides are returned to their position of normal straight alignment after elevation and removal of a loading pattern, the foremost bottles will rotate against the edges of the bottle stops 226 in a clockwise direction, and will again move forwardly, because of bottle feed pressure, in aligned rows between the bottle stops 226 and the bottle separators 228 of the bottle lift assembly D. It should be noted that the bottle feed pressure against the bottle stops 226 is prevented from exceeding a reasonable design maximum by means of the bottle stops 152 and 154.

The particular cooperation between the swinging guide plates and the bottle stops, resulting in the rolling or rotational forward movement of the foremost bottles, is of particular importance and represents a substantial improvement over known methods of loading pattern separation. The structure of the present invention eliminates all possibility of bottle tip-over and breakage, and substantially eliminates "scrubbing" between moving machine parts or other bottles and the label of the longitudinally adjacent bottles being separated during the operation of defining and removing a loading pattern of bottles.

For the purpose of determining the presence of a full bottle pattern on the bottle-lift platform, we provide a plurality of stop fingers 230 (see Figure 10). One stop finger 230 is provided for each row of bottles, four being required for the four-row three-deep pattern illustrated. Each stop finger 230 is freely rotatable about a pivot pin 232. A stop finger assembly support 234 is secured to the machine frame and serves to fixedly position a support bracket 236. Springs 238 serve to bias the stop fingers 230 in a vertically upward position for effecting contact with the foremost bottles of the adjacent rows, when such bottles have reached a predetermined forward position. A feeler bar 240 is rigidly carried for pivot movement by a horizontal rock shaft 242 and serves to provide a contact bracket 244 at its one end which engages a limit switch 246.

In the normal arrangement of parts, without abutment of four bottles against all four stop fingers 230, the feeler contact bracket 244 serves to engage and hold open the limit switch 246. The switch 246 is spring biased to a closed position, but is not free to move to such position because of obstruction by the feeler contact bracket 244. As long as one stop finger is held in its vertical position

by its spring 238, the spring bias of the limit switch 246 is insufficient to effect movement of the feeler contact bracket 244 and allow the switch to close. When, however, a full four rows of bottles are present on the lift assembly with the foremost bottles in a predetermined forward position, all of the stop fingers 230 will be engaged and pivoted to positions of clearance with respect to the feeler bar 240, thereby permitting the feeler contact bracket 244 and feeler bar 240 to be moved by the closing bias of the limit switch 246.

In this way, the switch 246 will automatically close when a full bottle pattern is present on the lift assembly. It is apparent that the foremost bottle of each of the side-by-side rows will only effect pivoting of the stop fingers when additional bottles immediately therebehind serve to transmit a sufficient forward feed pressure. This occurs only when a full loading pattern is present on the bottom plugs 190 which form the bottle-lift platform. Subsequent actuation of the bottle-guide swing-operating cylinder 112 will swing the rows of bottles immediately behind the loading pattern about one-half bottle diameter to one side in rolling contact about the bottle stops 226. The bottle-lift platform may thereafter be elevated a height of about 3 inches to raise the bottles supported thereon to the transfer head and bottle clamp unit E.

A transfer head is indicated generally at 250 on Figure 8, and includes a head carriage, bottle clamp unit, jaw operating drive, and transfer cylinder. A front carriage 251 and a rear carriage 252, are supported by means of horizontal and vertical axis rollers 253 and 254, respectively, on frame channel members 255. Tie means comprising a tie bar 256 and a tie rod 258 serve to rigidly interconnect the rear carriages 251 and 252 in spaced relation. For purposes of illustration, both tie bar and tie rod arrangements are shown, but it will be understood that a pair of carriage connector means of either one type or the other would actually be employed rather than one of each as shown.

A plurality of bottle clamp units 260, 261, and 262 are supported in suspended relation from the tie means 256 and 258, and may be adjustably positioned between the front and rear carriages 251 and 252 to provide the desired bottle pattern spacing. It will be apparent that a greater number of smaller bottle clamp units may be employed where a different pattern is desired for handling bottles of smaller size. The head carriage assembly and the bottle clamp units carried thereby form the transfer head 250, and may be shifted forwardly as a unit by movement of the rollers 253 and 254 along the frame channel members 255.

The bottle clamp units 260 to 262 each comprise (as best seen in Figure 11) a housing 264 having a housing cover 266. The housing 264 is recessed to form a pair of spaced slide chambers 268 and 270 which are adapted to receive the enlarged head portions of a block slide member 272. The head portions of the block slide member 272 are each formed with a pair of cam slots 274 and 276. Cam followers 278 and 280 of clamp slide blocks 282 and 284 are received within the cam slots 274 and 276. The slide blocks 282 and 284 are received within lateral slide chambers 281 and 283 formed in the housing 264 at opposite sides of a slide retainer element 285. The slide blocks 282 and 284 fixedly carry a pair of opposed gripping jaws 286 and 288, respectively, having resilient grippers 290 adapted to engage and firmly grasp the neck of a bottle. A fiber stop bar 292 is suspended between the gripping jaws 286 and 288 by a support means 294 which extends downwardly from the housing 264.

The block slide member 272 provides an actuator end 298 carrying a roller 300. A jaw clamp operating bar 302 provides an elongated roller track for cooperation with the roller 300. In this manner, a positive interconnection between the block slide member 272 and the clamp operating bar is provided, while permitting recipro-

cation of the transfer head in a horizontal plane. As best seen in Figures 8 and 9 of the drawing, the operating bar 302 is transversely movable on guide shafts 304, which slidably extend through suitable bosses 305 rigidly carried by the machine frame. A pair of slide knobs 306 extend upwardly from the operating bar 302 and effect open yoke connections with a pair of actuating clamp levers 308, which are rigidly connected to a rock shaft 310. Bearings 311 and 312 serve to rotatably support the rock shaft 310 in a fixed horizontal position. A power clamp lever 314 is rigidly secured to the rock shaft 310 and is connected by means of a link 316 to the piston rod 318 of a pneumatic jaw-operating cylinder 320.

It will be apparent that actuation of the jaw-operating cylinder 320 to effect reciprocation of the piston rod 318 will serve to laterally shift the jaw clamp operating bar 302, and thereby reciprocate the actuator ends 298 of the block slide members 272 of bottle clamp units 260-262. Reciprocation of the block slide members 272 serves to slide the head portions thereof within the slide chambers 268 and 270. As best seen in Figure 12 of the drawing, movement of the block slide member 272 causes movement of the cam slots 274 and 276 of each head portion relative to the axially fixed clamp side blocks 282 and 284. The cam followers 278 and 280 will cooperate with the cam slots 274 and 276 to effect transverse sliding movement of the clamp slide blocks within the slide chambers 281 and 283. In this manner, the gripping jaws 286 and 288 may be moved toward and away from each other by reciprocation of the block slide member 272. The jaw operating cylinder 320 thereby effects simultaneous opening and closing of the gripping jaws of each of the bottle clamp units 260-262.

As best seen in Figures 13 and 14, the resilient grippers 290 of the gripper jaws 286 and 288 serve to positively engage the necks of each of the bottles therebetween. It will be apparent that the top cap surface of each bottle will be raised into abutting engagement with the fiber stop bars 292 of the bottle clamp units as the bottles are raised by the bottle lift assembly. The resiliently mounted bottom plugs 190 which form the bottle lift platform will permit appropriate adjustment for bottles of varying heights while effecting horizontal alignment of the tops of all bottles in a single plane. It is well-known that commercially produced bottles of a particular capacity, although intended to be uniformly identical in shape and size, vary considerably in vertical height. The neck portions of such bottles, however, are usually substantially uniform, or at least subject to negligible variation among bottles of the same kind. By aligning the top caps in the manner described, it is possible to enable the transfer head and bottle clamp unit E to effect uniform gripping of all the bottles of a loading pattern with great reliability and a minimum hazard of bottle breakage.

It should be noted that immediately prior to jaw closing about the necks of the bottles of the loading group, the bottles of each of the spaced rows are in consecutive contacting or abutting relation. Frequently it is desirable to separate the bottles when positioned in loaded relation within a case by means of a cardboard partition grid, so as to avoid direct bottle-to-bottle contact and minimize risk of breakage. Some initial spacing between the abutting bottles of the loading group rows may readily be accomplished by spacing the respective gripping units longitudinally from each other a sufficient distance so that as the bottles are gripped by the closing jaws the bottle caps will slide against the fiber stop bars 292 and the bottles will be longitudinally spaced from each other.

The entire transfer head 250 is reciprocable in a horizontal plane from a rear or bottle gripping position directly overlying the lift platform of the bottle lift assembly to a forward or bottle releasing position directly overlying a case elevator assembly F, to be hereinafter described in detail. Reciprocation of the transfer head

250 is effected by means of a pneumatically operated head transfer cylinder 322 (see Figure 8). A piston rod 324 is rigidly connected by means of a head flange 325 to the rear carriage 252 of the transfer head 250, and axial movement of the piston rod 324 serves to move the head assembly 250 from a bottle gripping position to a case loading position and return.

A normally open limit switch 326b (see Figure 8) is fixedly secured to the machine frame, and cooperates with one end of a trip 326 carried by the jaw clamp operating bar 302 so as to effect switch closure when the bottle-gripping jaws of the units 260-262 are closed. A normally open limit switch 326a (see Figure 8) is fixedly secured to the machine frame and cooperates with the other end of the trip 326 so as to effect switch closure when the bottle-gripping jaws are open. A normally open limit switch 327 (see Figure 9) is fixedly secured to the machine frame, and cooperates with a trip 327a carried by an elongated trip bar 215 which is rigidly secured to the bottle lift platform so as to effect switch closure when the platform is in its full elevated position. A normally open limit switch 328 (see Figure 8) is carried by the rear carriage 252 of the transfer head, and cooperates with a trip 328a mounted on the machine frame so as to effect switch closure when the transfer head 250 is in its full back position. A normally open limit switch 329 (see Figure 8) is carried by the front carriage 251 of the transfer head, and cooperates with a trip 329a mounted on the machine frame so as to effect switch closure when the transfer head 250 is in its full forward position. A normally open limit switch 490 (see Figures 8 and 10) is mounted on an overhanging bracket 492 secured to the jaw operating bar 302. A cooperating trip 490a is secured to the transfer head carriage tie means 256 so as to effect contacting engagement with the switch 492 only when the bottle-gripping jaws are closed. Figure 8 shows the jaws in closed position, and it will be apparent that upon forward movement of the head 250 the trip 490a will effect closing of the switch 490. After release of the bottles into a case by opening of the jaws, the switch 490 and its trip 490a will no longer be in linear alignment because of lateral movement of the bracket 492 with the jaw operating bar 302, and as the transfer head moves back to a bottle-gripping or rear position the trip 490a will not engage the switch 490. It will be apparent that as the transfer head 250 moves forwardly with a full loading pattern held by the closed gripping jaws, the switch 290 will be closed for energizing a suitable solenoid for controlling a valve to regulate a supply of compressed air to the cylinder 112.

As best seen in Figures 3 and 15, the case elevator assembly F includes a case elevator platform 330 disposed in horizontal alignment upon a pneumatic elevator lift cylinder 332. An elevator housing 334 encloses the operating parts of the elevator assembly and is fixedly mounted on the machine frame. A back plate 336 and a pair of case guide angles 338 and 340 are fixedly secured to the supporting surface of the platform 330. The guide angles 338 and 340 are positioned in parallel spaced relation, and are adjustably mounted to permit variation of the separating distance therebetween to accommodate cases of different widths. A plurality of 65 case bearing strips extend across the platform 330 in the direction of case movement, and further serve to support and guide the case in its movement with respect to the platform 330.

A slide plate or guide 344 is rigidly secured to the machine frame and cooperates with an elevator slide member 346 carried by the elevator platform 330 at its rear edge (see Figure 15). In this manner, the elevator platform 330 is uniformly guided during vertical up and down movement. A bearing plate 348 carried by a piston rod 350 of the lift cylinder 332 is rigidly secured

to the bottom surface of the platform 330. A piston 352 serves to actuate the piston rod 350 in response to pneumatic pressure within the cylinder 332. In this way, the platform 330 may be vertically reciprocated.

A trip pin 354 is carried by the lift cylinder 332, and is vertically slidable within a guide block 356. A roller 358, carried by the trip pin 354 at its upper end, extends a slight distance upwardly through the elevator platform 330, and is upwardly biased by a supporting spring body 360. A contact head 362 is carried by the trip pin 354 at its lower end, and is preferably vertically adjustable for varying the height of movement of the trip pin 354 to accommodate operation with cases of different selected heights. A limit switch 364 is fixedly mounted on the frame by means of a bracket 365. The switch 364 is normally biased open, and will be closed in response to a predetermined downward movement of the contact head 362 thereagainst. A trip plate 368 is hingedly connected to the supporting surface of the platform 330 in a position directly overlying and lightly contacting the roller 358. It will be apparent that the presence of a case on the elevator platform 330, in a condition of sufficient weight to exert actuating downward pressure against the trip plate 368, will serve to move the trip pin 354 downwardly and effect a closing of the limit switch 364. This condition will occur only when a full loaded case is present on the platform 330 with the elevator in its fully lowered position.

A trip plate 368, having an assembly of trip actuating elements substantially identical with the parts 354-362 and a limit switch 369 (shown only in Figure 26), is also hingedly connected to the supporting surface of the platform 330. The switch 369 is normally biased closed, and will be actuated to an open position when a full case is positioned on the trip plate 368. The trip plate 368 is of elongated form, and is so positioned on platform 330 as to provide an over-hanging portion extending beyond the forward edge of the platform with respect to the direction of case travel. A loaded case, therefore, will continue to engage the trip plate 368 and maintain the limit switch 369 in an open position until the case is fully off the platform 330. An empty case does not provide sufficient weight to depress the trip plate 368 to the distance necessary for actuating limit switch 369 to an open position.

As best seen in Figure 15, a trip rod 370 having a pivot 372 is mounted on the platform 330 and biased by spring means 374 in an inward direction, for engagement with the side of a case when positioned on the platform 330. The outer end of the trip rod 370 carries a contact head 376a which engages a limit switch 376, normally biased open, for actuating the switch to a closed position when a case is present on the elevator platform 330. The trip plates 366 and 368 effect an actuating movement in response to the substantial weight of a loaded case, whereas the trip rod 370 must respond to the relatively light weight of an empty case. Frequently, the case bottoms may become wet and therefore lacking in sufficient rigidity to effect actuation of a trip plate. The case sides, however, ordinarily remain dry and have sufficient structural rigidity to effect trip actuation. The trip rod 370, therefore, is positioned so as to operate against the side of a case rather than against the bottom as in the manner of trip plates.

A normally open limit switch 378 (see Figure 3) is fixedly mounted on the machine frame, and cooperates with a trip 378a carried by an elongated trip bar 377 which is rigidly secured to the back plate 336 of the case elevator. The trip 378a effects closure of the switch 378 when the case elevator is in its full up position. A second limit switch 379 is fixedly mounted on the machine at a point about midway between the lower and upper limits of the vertical stroke of the case elevator platform. The trip 378a also serves as a trip to close

the switch 379 when the case elevator is at about the half-way point of its lowering travel.

The loading station G, where the transfer head and case elevator cooperate to effect loading of the bottles into the case, includes a funnel plate assembly, funnel guide, and funnel plate guard. As best seen in Figure 3 and Figures 16 to 19, a funnel plate 380 is provided to surround and confine the bottle loading pattern as the empty case is elevated in surrounding relation about the bottles during loading. The funnel plate 380 is centrally cut away to provide an over-size peripheral outline conforming to the external contour of the bottle pattern. A plurality of cross braces 382 define the rows of the loading pattern and provide fixed support means for mounting a plurality of spring fingers 384. It will be apparent that relative movement between the funnel plate 380 and the bottle loading pattern will result in resilient contacting engagement of each bottle by a surrounding plurality of four spring fingers 384, thereby guiding and maintaining alignment of the bottles during the loading operation.

A pair of mounting brackets 386 are fixedly positioned relative to the machine frame and serve to support a pair of vertical guide rods 388. The upper ends of the brackets 386 also serve as an abutment support upon which the funnel plate 380 rests when in a lowered position. A pair of roller brackets 390 are secured to the edges of the funnel plate 380, and each carry an inwardly concave roller 392, having nylined bushings for smooth rotation about supporting roller pins 394. The rollers 392 cooperatively engage the vertical guide rods 388 to permit smooth vertical reciprocation of the funnel plate 380. It will be apparent that as an empty case is raised by the case elevator, its upper edge will contacting engage the funnel plate 380, thereby positioning the spring fingers 384 within the walls of the case to define the loading positions of the bottles to be received. As a case is further elevated, the funnel plate 380 will be raised therewith, and the loading pattern of bottles will pass therethrough as the case is moved to its uppermost position of surrounding relation about the bottles. As the loaded case is lowered, the funnel plate 380 will fall with it to its lower starting position upon the mounting brackets 386.

Although not shown in connection with the particular construction disclosed, it will be understood that a suitable limit switch and trip may be provided to discontinue operation of the machine in the event that the funnel plate 380 should stick or jam in its raised position and fail to fall to the position shown in Figure 3 after a case loading. Obviously, the funnel plate 380 would obstruct the next loading operation, if in its raised position, causing bottle breakage and possible damage to the machine. We have found, however, that the novel guide and roller arrangement provided by the present invention for vertical sliding of the guide plate precludes any possibility of sticking or jamming in raised position, and eliminates any practical need for a safety switch arrangement.

The cases which are customarily employed for bottle loading are provided with cover flaps of various forms, which frequently present an obstruction problem during the loading operation. It is essential to prevent any possibility of a case having one or more cover flaps lowered in closed position when the case is elevated to receive a bottle pattern. For this purpose, we provide a plurality of spring guides 400 (see Figures 17 and 18) which are carried by the funnel plate 380 in downwardly extending relation therefrom at its opposite ends. The guides 400 serve to engage the side of a case c and center the case in properly aligned position below the funnel plate 380. Additional spring guides 402 are similarly carried by the funnel plate 380 (see Figure 19), and serve to retain case flaps f in a lowered position adjacent the sides of the case c.

As best seen in Figure 3 of the drawing, a guard hous-

ing 410 surrounds the loading station G, and is provided with a pair of transparent side plates 412 and a front plate 414 to permit visual observation. The front plate 414 to permit visual observation. The front plate plate 414 is mounted in a hinged door frame 416 to permit access to the loading station.

The empty-case feed section H and the loaded-case discharge section I, together with the mechanical drive for effecting case feed J, are best shown in Figure 3 of the drawing. Although the case feed arrangement shown is from the right-hand to the left-hand side of Figure 3, it will be understood that the arrangement may be reversed, if desired, to provide feed in the opposite direction, from left to right.

A case feed conveyor is provided, and includes a conveyor frame 420 which is rigidly mounted on the machine frame A and is suitably supported on vertically adjustable supports 422. The conveyor frame 420 carries a fixed horizontal case plate 424, upon which the cases are supported and slid forwardly toward the case elevator during operation of the machine. A flight chain assembly is provided, and includes a set of flight chains 426, carrying a plurality of spaced flight bars 428, and mounted for driving movement on sprocket wheels carried by a drive shaft 430 and an idler shaft 432. The conveyor frame 420 also provides a pair of longitudinally extending case guides 434 and 435, which position the empty case during its movement along the conveyor, and a pair of flap guides 436 and 437, which serve to maintain the cover flaps of the case in downwardly open positions.

The mechanical drive for the case-feed conveyor includes a motor 440 having an output shaft 442 which carries a drive sprocket 444. A drive chain 446 connects the motor 440 to a clutch sprocket 448 of the clutch shaft 450 of a single revolution clutch 452 (see Figure 20). A power gear 454 is carried by the clutch shaft 450, and meshes with a drive shaft 430. A clutch actuator means 458 provides a vertically reciprocable clutch pin 459 which is controlled by means of a solenoid 460. Energizing of the solenoid 460 serves to effect downward movement of the clutch pin 459 to permit clutch engagement, thereby enabling power to be transmitted from the motor 440 to the case feed conveyor.

A trip rod 462 is pivotally mounted on the case guide 435 and inwardly biased in the manner of trip rod 370, as described in connection with the case elevator assembly. The outer end of the trip rod 462 carries a contact head 462a which engages a limit switch 466 (see Figure 2). The limit switch 466 is normally biased in closed position, and operates to energize the solenoid 460 for withdrawing the clutch pin 459 and transmitting driving power from the motor 440 to the conveyor flight chains 426. An empty case placed on the case plate 424 will have its lower rear edge engaged by a moving flight bar 428, and will be slid forwardly along the plate 424 between the case and flap guides 435-437. As a case engages the contact head 462a of the trip rod 462, the limit switch 466 will be opened, de-energizing the solenoid 460 and permitting the spring biased clutch actuator means 458 to elevate the clutch pin 459, thereby disengaging the clutch 452 and interrupting the transmission of driving power after the completion of a single clutch shaft revolution. In this way, cases will be automatically fed only as required by the loading operation.

A case discharge conveyor is provided at the side of the case elevator opposite the case feed conveyor. The discharge conveyor includes a roller frame 470 having a plurality of rollers 472. The frame 470 may be secured to the machine frame by means of pivot brackets (not shown) for permitting adjustment of the traveling level to any desired position of downward inclination. In this manner, the discharge conveyor will effect gravity removal of the loaded cases away from the machine.

In order to effect controlled actuation and coordinated

operation of the bottle lift platform, bottle-gripping jaws, and transfer head movement, we provide a plurality of air control valve and limit switch trips which are regulated by the up and down movements of the bottle lift and case elevators during operation of the machine. As seen in Figure 9, the trip bar 215 which carries the limit switch trip 327a also carries an air valve trip 480a and a second limit switch trip 482a. An air valve 480 is fixedly mounted on the machine frame, and is normally biased in a valve closed position. The air valve 480 serves to control flow between a compressed air source line 484 and an air supply line 485 leading to the jaw-operating cylinder 320 at an end thereof for effecting forward movement of the piston rod 318 and consequent closing of the bottle-gripping jaws.

A limit switch 482 is fixedly mounted on the machine at a point about midway between the lower and upper limits of the vertical stroke of the bottle lift platform. The trip 482a serves to close the switch 482 when the bottle lift is at about the half-way point of its lowering travel.

As seen in Figure 3, the trip bar 377 also carries an air valve trip 486a which cooperates with an air valve 486 fixedly mounted on the machine frame. The air valve 486 is normally biased in a valve closed position and serves to control flow between a compressed air source line 488 and an air supply line 489 leading to the jaw-operating cylinder 320 at an end thereof for effecting rearward movement of the piston rod 318 and consequent opening of the bottle gripping jaws.

Referring particularly to Figure 26 of the drawing, we have diagrammatically illustrated the electrical control circuit for effecting automatic and manual operation of the various machine functions. In particular, our control circuit provides complete fail-safe operation of the machine under any condition of mechanical or pneumatic malfunctioning.

In Figure 27, a diagrammatic view of the front end of the case loader is shown for the purpose of illustrating the particular mounting position of the various electrical switches, wiring elements, and other electrical control devices. A first large box 510 is provided on the front side of the case feed conveyor housing. Within the box 510 are positioned a pair of motor starters 502 and 504 for the bottle conveyor and case feed conveyor motors 108 and 440, respectively. A manual disconnect switch 506 extends from the box 510, and permits the machine operator to connect or disconnect the machine from its electrical power supply. A transformer is carried within the box 510, and serves to provide a current of reduced voltage to the various electrical controls and solenoids.

A second control box 520 is mounted upon the case-feed conveyor frame above the case flap guide 437. The box 520 provides various manual control buttons for regulating the machine operation to permit clearing of the machine in the event of bottle or debris jamming. Box 520 provides an elevator-up button 522, and a red pilot light 528 which is connected to the full pattern limit switch 246 to permit lighting when the bottle pattern 60 is not complete and switch 246 is open.

A third control box 530 is also mounted on the case-feed conveyor. The box 530 provides an additional group of manual controls including a conveyor start button 532, a conveyor stop button 534, a case feed button 536, and a cycle button 538 for shutting off the controls.

A fourth control box 540 is mounted at the top of the machine frame above the bottle gripping head assembly. The box 540 encloses a relay 542 and a terminal mounting strip which permits wiring of the various limit switches at a position for convenient access.

Referring again to the circuit diagram of Figure 26 we have indicated a plurality of solenoids which serve to actuate the various valves for controlling the operation 75 of the pneumatic cylinders which effect guide plate swing-

ing, head transfer, jaw gripping, and elevator raising and lowering. These solenoids include an elevator-up solenoid 550 and an elevator-down solenoid 552, which control a suitable valve for regulating the up and down actuating movements of the case elevator cylinder 332. Movement of the swinging guide plates 52, 54, 64-68 in a laterally sideways manner across the traveling level of the bottle-feed conveyor 80 to obstruct forward bottle movement is controlled by a closing solenoid 554, which controls a suitable valve for regulating the swing-operating cylinder 112. A return solenoid 564 similarly controls the swing-operating cylinder 112 for longitudinally aligning the swinging guide plates to permit free forward bottle flow. A bottle lift up solenoid 558 and a bottle lift down solenoid 560 are provided to control a suitable valve for regulating the up and down actuating movements of the bottle lift cylinder 212. Similarly, a head forward solenoid 562 and a head return solenoid 556 effect regulation of the horizontal reciprocation of the transfer head 250 between its bottle-gripping and bottle-releasing positions.

A suitable fuse 570 is provided in the circuit at the current supply contacts in conventional manner. Further, a mechanical counter 572 is connected to the limit switch 369, which responds to the discharge of a full case off of the elevator, thereby registering the number of cases loaded during the operation of the machine. An optional safety switch, which may be provided if desired to permit energizing of the head forward solenoid 562 only when the funnel guide plate 380 has dropped to its lowered position, is indicated at 574. Also, the manual push button 526 may be suitably ganged to a normally closed switch 526a to effect deenergizing of the bottle lift up solenoid 558 when the push button 526 is closed for manual forward actuation of the transfer head.

Practical operation

The practical operation of the case loader disclosed by the present invention will be described by outlining the course of movement of a plurality of bottles from the point of initial introduction onto the bottle feed conveyor, through a case loading cycle, to discharge of a fully loaded case from the machine. Reference may be had to Figures 21 through 25 of the drawings for a diagrammatic presentation of the basic operations performed by the case loader, Figure 26 for a detailed showing of the electrical controls for regulating the pneumatic actuation of the various mechanical functions of the machine, and Figure 28 for a charting of each of the machine operations in their cooperative inter-relation.

The operator effects starting of the machine by closing the manual disconnect switch 506, thereby connecting the motors and control circuitry to a suitable current supply. By pressing the conveyor start button 532, the motor starters 502 and 504 will initiate power operation of the bottle-feed conveyor motor 108 and the empty-case feed conveyor motor 440, respectively. In this way, the bottle-feed conveyor will be continuously driven, and mechanical driving power will be provided for use as required by the empty-case feed conveyor.

The operator may then initiate automatic cycling operation of the machine by throwing the operator's switch 538 to the "on" position. Assuming next that a supply of bottles is introduced onto the bottle-feed conveyor at its receiving end, and that an empty case is placed on the case feed conveyor, the machine will effect case loading operation. The bottle feed conveyor 80 will serve to move the bottles forwardly thereon and orient them into a plurality of spaced parallel rows of consecutively abutting series. The bottle rows will be delivered from the conveyor onto the bottle-lift platform so as to define a loading pattern of bottles thereon. The presence of a full bottle pattern on the bottle lift will serve to effect a closing of switch 246, which is in series with switches 369, 376 and 329. Assuming that the presence of the

empty case on the case feed conveyor, with the case elevator in a lowered position, has previously effected energizing of the case feed clutch solenoid 460, an empty case will have been fed onto the elevator platform, thereby causing switches 369 and 376 to be closed. Also, the swinging guides closed solenoid 554 will have been energized to relieve the forward feeding pressure exerted against the loading pattern, by actuating the swing-operating cylinder 112, and move the bottle guides laterally.

If the transfer head 250 is in its full back or bottle-gripping position, switch 328 will be closed, thereby energizing the bottle lift up solenoid 558 for actuating the cylinder 212. The bottle lift will be raised, and when in its full up position will effect closing of switch 327, which serves to cock the relay 542 and energize the bottle lift down solenoid 560. At the same time, raising of the bottle lift serves to open the valve 480 and actuate the jaw operating cylinder 320 to effect closing of the jaws. Closing of the jaws will serve to close the safety 326b and cock the relay 542.

At this point the transfer head will have firmly gripped the bottles of the loading pattern so as to suspend them in downwardly depending relation therefrom. As the bottle lift goes down, switch 482 will be closed, thereby energizing the head forward solenoid 562, which controls forward actuation of the transfer head cylinder 322. It should be noted that unless the bottle gripping jaws have been closed so as to effect a closing of the switch 326b, the bottle lift will remain up and the transfer head will stay back.

As the transfer head moves forward with the gripping jaws closed, the switch 490 will be closed, thereby energizing the solenoid 564 and actuating the swing-operating cylinder 112 to move the swinging guides to a longitudinally aligned or bottle flow position and permit filling of the next loading pattern on the bottle lift. When the head reaches its full forward position, the switch 329 will be closed. If the next empty case is on the case elevator (closing switch 376), any previous full case is completely off the elevator (closing switch 369), and the next full bottle pattern is on the bottle lift (closing switch 246), then the elevator up solenoid 550 which controls the case elevator cylinder 332 will be energized so as to send the case elevator up.

As the case elevator raises the empty case upwardly, the funnel guide plate 380 will be carried with it, and the bottles of the loading pattern will slide therethrough into guided positions of loaded orientation substantially within the case. When the case is in its full up position, switch 378 will be closed, and at the same time valve 486 will be opened, thereby energizing the case elevator down solenoid 552 and actuating the jaw operating cylinder 320 to open the jaws. The swinging guides closed solenoid 554 will also be energized to relieve the forward feeding pressure exerted against the loading pattern on the bottle lift, and will further serve to cock the relay 542.

As the case elevator goes down, switch 379 will be closed, thereby energizing the head return solenoid 556, which controls the cylinder 322. The positioning of switch 379 permits a necessary time lag between closing of switch 378 and switch 379 to allow the bottles to drop the small remaining distance to the bottom of the case before the transfer head returns to its back position. It should be noted that opening of the jaws at the loading station also serves to close safety switch 326a. Unless the safety 326a is closed, the transfer head will not be permitted to return to the bottle gripping station.

The loading cycle will be continuously repeated as long as bottles and empty cases are fed to the machine. It will be apparent that each step of the loading operation must be properly and completely performed before the next subsequent operation can be effected. In this manner, completely fail-safe operation of the machine may be achieved, thereby preventing possible bottle breakage.

or damage to the machine parts. The various manual controls serve to permit manual actuation of any of the machine operations, if desired, for purposes of clearing the machine or initiating stopping and starting at any point during a cycle of operation.

Changes may be made in the construction and arrangement of the parts of our case loader without departing from the real spirit and purpose of our invention, and it is our intention to cover by the claims any modified forms of structure or use of mechanical improvements which may be reasonably included within their scope.

We claim:

1. In a case loader, bottle-feed conveying and guiding means comprising a conveyor having a substantially horizontal traveling level for supporting a plurality of bottles in vertically upright positions thereon, said traveling level moving in a forward direction from a receiving end to a discharge end, guide means for orienting bottles into spaced parallel rows of consecutively abutting series while carried forwardly by said conveyor, said guide means defining an initial bottle-carrying surface on said traveling level of relatively constricted lateral width at said receiving end and diverging outwardly to a terminal-carrying surface of relatively broad lateral width at said discharge end, whereby bottles may be carried by said conveyor from said receiving end in outwardly diverging manner toward said discharge end, first pressure gate means for obstructing the forward movement of bottles on said initial bottle-carrying surface to relieve forward pressure exerted by the conveyor-fed bottles against one another on said terminal-carrying surface, and second pressure gate means for obstructing the forward movement of bottles on said terminal-carrying surface at the discharge end of said conveyor to prevent forward movement and discharge of the bottle rows from the conveyor.

2. In a case loader, bottle-feed conveying and guide means comprising a conveyor having a substantially horizontal traveling level for supporting a plurality of bottles in vertically upright positions thereon, said traveling level moving in a forward direction from a receiving end to a discharge end, and guide means for orienting bottles into spaced parallel rows of consecutively abutting series while carried forwardly by said conveyor, said guide means comprising a plurality of elongated vertical guide plates disposed in parallel spaced arrangement, said guide plates being secured to a pivot axis at their rear ends and to a swing-actuating means at their forward ends, whereby said swing-actuating means serves to effect simultaneous pivoting of said guide plates to effect a lateral swinging thereof across the conveyor traveling level, a plurality of laterally spaced stop elements immediately adjacent the forward ends of said guide plates and each normally in longitudinal alignment with a corresponding one of said guide plates, said stop elements serving to permit forward movement of the bottle rows therebetween for discharge from the conveyor when said guide plates are in normal alignment and each serving to obstruct forward feed and discharge of a corresponding one of the bottle rows from the conveyor when said guide plates are swung laterally.

3. In a case loader, bottle-feed conveying and guide means comprising a conveyor having a substantially horizontal traveling level for supporting a plurality of bottles in vertically upright positions thereon, said traveling level moving in a forward direction from a receiving end to a discharge end, and guide means for orienting bottles into spaced parallel rows of consecutively abutting series while carried forwardly by said conveyor, said guide means comprising a plurality of elongated vertical guide plates disposed in parallel spaced arrangement and mounted for pivotal swinging movement laterally across the conveyor traveling level, means for swinging said conveyor guide plates, support means positioned at the discharge end of said conveyor for receiving a forward

plurality of said bottle rows when discharged forwardly from the conveyor by the forward moving tendency of the bottles immediately therebehind, the bottles received on said support means defining a loading group, a plurality of laterally spaced stop elements fixedly disposed

5 between the forward terminal edges of said conveyor guide plates and said loading pattern support means each in longitudinal alignment with a corresponding one of said guide plates, whereby the bottle rows may be fed 10 forwardly therebetween, swinging movement of said conveyor guide plates serving to shift the bottle rows therebetween transversely to one side of the rows of the loading pattern with the foremost bottles of said conveyor-supported rows effecting rolling cooperation with said 15 fixed stop elements to effect complete separation of the conveyor-supported rows from the loading pattern rows and preventing forward movement of the conveyor-supported rows.

4. In a case loader, a bottle lift platform adapted 20 to receive a loading pattern of bottles and support them in vertically upright position thereon, said bottle lift platform comprising a plurality of collapsible bottom plugs each serving to support a bottle of the loading pattern, and a transfer head disposed above said bottle lift platform 25 and having bottle-gripping means operative when closed to grasp the upper portions of the bottles of the loading pattern and hold them in downwardly suspending relation, said collapsible bottom plugs cooperating with said transfer head to uniformly align the tops of the bottles of the loading pattern in a fixed plane.

5. In a case loader, a bottle lift platform adapted to receive a loading pattern of bottles and support them in vertically upright position thereon, said bottle lift platform comprising a plurality of collapsible bottom 30 plugs each serving to support a bottle of the loading pattern, a transfer head disposed above said bottle lift platform and having bottle-gripping means operative when closed to grasp the upper portions of the bottles of the loading pattern and hold them in downwardly suspending 35 relation, means for elevating said bottle lift to raise the loading pattern to a position for being gripped by said transfer head, said collapsible bottom plugs cooperating with said transfer head when the bottle lift is fully elevated to uniformly align the tops of the bottles of the loading pattern in a fixed plane.

6. In a case loader, a bottle lift platform adapted to receive a loading pattern of bottles and support them in vertically upright position thereon, said bottle lift platform comprising a plurality of collapsible bottom plugs each serving to support a bottle of the loading pattern, a transfer head disposed above said bottle lift platform and having bottle-gripping means operative when closed to grasp the upper portions of the bottles of the loading pattern and hold them in downwardly suspending relation, stop means carried by said transfer head and providing a plurality of co-planar contact surfaces, means for elevating said bottle lift to raise the loading pattern to a position for being gripped by said transfer head, said collapsible bottom plugs cooperating with said transfer head when the bottle lift is fully elevated to enable the tops of all of the bottles of the loading pattern to effect contacting engagement with said planar contact surfaces irrespective of variations in bottle heights, thereby uniformly aligning the tops of the bottles of the loading pattern in a fixed plane.

7. In a case loader, bottle-feed conveying and guide means operative to carry a plurality of bottles in a forward direction while orienting them into spaced parallel rows of consecutive abutting series, a bottle lift platform positioned at the discharge end of said conveying means to receive a forward plurality of the bottles of said rows and define a loading pattern thereon, the bottles of said loading pattern comprising spaced parallel rows of consecutively abutting series, said bottle lift platform comprising a plurality of collapsible bottom plugs each

serving to supporting a bottle of the loading pattern, a transfer head disposed above said bottle lift platform and having bottle-gripping means operative when closed to grasp the upper portions of the bottles of the loading pattern and hold them in downwardly suspending relation, stop means carried by said transfer head and comprising a plurality of fiber contact bars providing coplanar contact surfaces, means for elevating said bottle lift to raise the loading pattern to a position for being gripped by said transfer head, said collapsible bottom plugs cooperating with said transfer head when the bottle lift is fully elevated to enable the tops of all of the bottles of the loading pattern to effect contacting engagement with the said contact bar surfaces irrespective of variations in bottle heights, the bottle-gripping means of said transfer head operating when closed about said elevated loading pattern to automatically effect spaced separation of the consecutively abutting bottles of each of the loading pattern rows by sliding movement of the bottle tops against the contact bar surfaces.

8. In a case loader, bottle-handling means comprising a transfer head for carrying a predetermined loading pattern of bottles in downwardly suspending relation, said transfer head including a plurality of bottle-gripping units each operative when closed at a bottle-gripping station to grasp the upper portions of the bottles of said loading pattern and hold them in downwardly suspending relation, said bottle-gripping units each having a stop bar against which the tops of the bottles gripped thereby may be positioned in contacting engagement, the stop bars of the respective bottle-gripping units lying in substantially the same fixed plane whereby the tops of all of the bottles suspended from said transfer head will be uniformly aligned in said fixed plane, said bottle-gripping units each operative when opened at a bottle-releasing station to simultaneously release all of the bottles of said loading group to effect a loading operation.

9. In combination with a case loader having a transfer head for fixedly suspending a loading pattern of bottles and a case elevator for raising an empty case upwardly to a position of surrounding relation about said loading pattern, guide means for facilitating entry of the loading pattern into the case, comprising an apertured funnel plate dimensioned so as to surround and confine the loading pattern, resilient means carried by said funnel plate and defining oriented paths of movement for the respective bottles of the loading pattern through said funnel plate, a pair of roller brackets carried by said funnel plate at opposed edges thereof, each of said brackets rotatably supporting an outwardly open roller, and a pair of fixedly mounted vertical guide rods positioned so as to cooperatively engage the outer rolling surfaces of said rollers and permit vertical reciprocation of said funnel plate between said case elevator and said transfer head, whereby upon raising of an empty case by said case elevator into contacting engagement with the lower surface of said funnel plate further raising of said case will serve to raise said funnel plate and effect passage of said loading pattern therethrough to properly position said loading pattern substantially fully within said case.

10. In combination with a case loader having a transfer head for fixedly suspending a loading pattern of bottles and a case elevator for raising an empty case upwardly to a position of surrounding relation about said loading pattern, guide means for facilitating entry of the loading pattern into the case, comprising an apertured funnel plate dimensioned so as to surround and confine the loading pattern, resilient means carried by said funnel plate and defining oriented paths of movement for the respective bottles of the loading pattern through said funnel plate, a pair of roller brackets carried by said funnel plate at opposed edges thereof, each of said brackets rotatably supporting an outwardly open roller, a pair of fixedly mounted vertical guide rods positioned so as to cooperatively engage the outer rolling surfaces of said rollers and per-

mit vertical reciprocation of said funnel plate between said case elevator and said transfer head, whereby upon raising of an empty case by said case elevator into contacting engagement with the lower surface of said funnel plate further raising of said case will serve to raise said funnel plate and effect passage of said loading pattern therethrough to properly position said loading pattern substantially fully within said case, and guide means carried by said funnel plate for cooperation with the cover flaps of said case to retain them in downwardly open relation during case elevation.

11. In a case loader, bottle-handling means comprising a transfer head for carrying a predetermined loading pattern of bottles in freely suspended relation, said transfer head having pneumatically operated bottle-gripping means serving when closed at a bottle-gripping station to grasp the upper portions of the bottles of the loading pattern and hold them in downwardly suspending relation, said bottle-gripping means serving when opened at a bottle-releasing station to simultaneously release all of the bottles of the loading pattern and effect a loading operation, said gripping and releasing stations being located in horizontally spaced relation at substantially the same vertical elevation, pneumatically operated means for reciprocating said head in a substantially horizontal plane between said stations, and control means for regulating the actuation of each of said pneumatically operated means in a sequential operating cycle, whereby the loading pattern may be gripped at the bottle-gripping station by the transfer head, moved thereby to the bottle-releasing station and there released for effecting a loading operation, and the transfer head returned to the bottle-gripping station to repeat the cycle.

12. In a case loader, a transfer head having bottle-gripping means operative when closed to grasp the upper portions of a plurality of bottles and fixedly hold them in downwardly suspending relation, means for arranging a plurality of bottles in a predetermined loading pattern, pneumatically operated means for delivering said loading pattern to said transfer head, pneumatically operated means for opening and closing said bottle-gripping means, pneumatically operated means for moving said transfer head between a bottle-gripping station and a bottle-releasing station, pneumatically operated means for elevating a case upwardly about said loading pattern at said bottle-releasing station while said loading pattern is suspended relative to said case elevating means, and control means for regulating the actuation of each of said pneumatically operated means in a sequential operating cycle, whereby a full loading pattern may be suspended by said bottle-gripping means in fixed position to receive a case therearound and then released while disposed substantially fully within the case to complete a loading of the case with a minimum of bottle fall.

13. In a case loader, a transfer head having bottle-gripping means operative when closed to grasp the upper portions of a plurality of bottles and fixedly hold them in downwardly suspending relation, means for arranging a plurality of bottles in a predetermined loading pattern at a fixed bottle-gripping station, pneumatically operated means for delivering said loading pattern to said transfer head at said bottle-gripping station, pneumatically operated means for closing said bottle-gripping means to grasp the upper portions of said loading pattern bottles, pneumatically operated means for moving said transfer head and the loading pattern carried thereby from said bottle-gripping station to a fixed bottle-releasing station, pneumatically operated means at said bottle-releasing station for elevating a case upwardly about said loading pattern while fixedly held relative to said case elevating means, pneumatically operated means for opening said bottle-gripping means to release simultaneously all of said loading pattern bottles, and control means for regulating the actuation of each of said pneumatically operated means in a sequential cycle dependent upon the proper

completion of each preceding operation, whereby a full loading pattern may be suspended by said bottle-gripping means in fixed position to receive a case therearound and then released while disposed substantially fully within the case to complete a loading of the case with a minimum of bottle fall.

14. In a case loader, a transfer head having bottle-gripping means operative when closed to grasp the upper portions of a plurality of bottles and fixedly hold them in downwardly suspending relation, means for arranging a plurality of bottles in a predetermined loading pattern beneath said transfer head at a fixed bottle-gripping station, pneumatically operated means for elevating said loading pattern upwardly toward said transfer head at said bottle-gripping station, pneumatically operated means for closing said bottle-gripping means to grasp the upper portions of said loading pattern bottles, pneumatically operated means for moving said transfer head and the loading pattern carried thereby from said bottle-gripping station to a fixed bottle-releasing station, pneumatically operated means beneath said transfer head at said bottle-releasing station for elevating a case upwardly about said loading pattern while fixedly held in downwardly suspending relation above said case elevating means, pneumatically operated means for opening said bottle-gripping means to release simultaneously all of said loading pattern bottles, and control means for regulating the actuation of each of said pneumatically operated means in a sequential cycle dependent upon the proper completion of each preceding operation, whereby a full loading pattern may be suspended by said bottle-gripping means in fixed position to receive a case therearound and then released while disposed substantially fully within the case to complete a loading of the case with a minimum of bottle fall.

15. In the case loader of claim 23, said electrical control means including a plurality of electrical switches responsive to opening and closing of said bottle-gripping means, full forward and return movement of said transfer head, and raising of said loading pattern elevating means, whereby failure of the bottle-gripping means to open at the bottle-releasing station serves to prevent actuation of the pneumatically operated means for returning

the transfer head to the bottle-gripping station, failure of the transfer head to fully return to the bottle-gripping station serves to prevent actuation of the pneumatically operated loading pattern elevating means, and failure of the jaws to close at the bottle-gripping station serves to prevent actuation of the pneumatically operated means for moving the transfer head forwardly.

16. A case loader comprising conveyor means operative to transport a plurality of uniformly oriented bottles, receiving means at the discharge end of said conveyor to receive a forward plurality of bottles as discharged from said conveyor and remove them as a unitary loading pattern, a pneumatically operated transfer head and bottle-gripping means to receive the bottles of said loading pattern and hold them in downwardly suspending relation, pneumatically operated means for moving said transfer head and the loading pattern suspended therefrom to a loading station, a pneumatically operated elevator means at said loading station for raising an empty case upwardly about said loading pattern in surrounding relation, said head serving to simultaneously release said bottles within said elevated case to complete a loading cycle, and electrical control means operative when energized to actuate a plurality of corresponding solenoids for regulating each of said pneumatically operated means, said electrical control means being automatically energized in response to the formation of a loading pattern and each successive step of the loading cycle.
